UNITED STATES PATENT OFFICE.

JOHN O. ELLIOTT, OF FARGO, NORTH DAKOTA.

CHECK BOOK.

Application filed September 21, 1922. Serial No. 589,678.

To all whom it may concern:

Be it known that I, JOHN O. ELLIOTT, a citizen of the United States, residing at Fargo, in the county of Cass and State of North Dakota, have invented certain new and useful Improvements in Check Books, of which the following is a specification.

My invention relates to check books, and more particularly to that class of books, designed for removably containing blank checks and record leaves, an object of the invention being the provision of improved means, for facilitating the issuance of checks; recording data relating thereto; and extending the utility thereof.

In the ordinary check book commonly in use, each check is accompanied by a stub upon which to record data with reference to the check. This involves striking a balance on each stub and bringing same forward to the next following stub, all of which entails tedious labor, and consumes considerable time.

Further, the stubs are bulky for filing, and compelled to be unnecessarily large, because they are usually a continuation of the check to which it is attached by a perforated tearing line.

The principal object of the present invention, is to provide a check book which will obviate all these disadvantages, by providing new and novel means, plainly visible, for recording and auditing the data of a plurality of issued checks on a single leaf, and on both sides thereof; new and novel means for removably holding a book of these recording leaves in the check book in a manner to be conveniently written upon, and be easily and conveniently readjusted to expose a new record leaf; novel means for holding a pad of check blanks in a convenient position in the check book; and novelly arranged blotting means, forming part of the pad of check blanks, for readily drying newly written matter on either the check or the record leaf.

An embodiment of my invention is illustrated in the accompanying drawings, wherein:—

Figure 1, is a perspective view of my improved check book, showing only the book of record leaves positioned therein.

Figure 2, is a sectional view on line 2—2 of Figure 1.

Figure 3, is an end view of the check book

showing the positions assumed by the check blanks and the record book, when the book is closed for pocket use.

Figure 4, is a perspective view of the closed check book covers.

Figure 5, is a sectional view on line 5—5 of Figure 4.

Figure 6, is a perspective view of the pad of check blanks, showing the blotter attached thereto.

Figure 7, is a perspective view of my improved book of record leaves; and

Figure 8, is a perspective view of the book of record leaves, showing the indicia on the outside thereof.

In the drawings, forming part of this specification, 1 and 2 designate the covers of the check book, preferably made of one piece of flexible material such as leather, having a line of fold 3, upon which it is bent to close the covers. One of the covers has an integral flap 4 formed by folding the material along the line of fold 5. The inner sides of the covers 1 and 2 are formed with oppositely disposed pockets 6 and 7, respectively.

Referring to Figure 7, 8 and 9 designate the covers of the book of record leaves which are foldable along the line 10 to enclose the contents. The book contains a plurality of record leaves 11, suitably bound between the covers. Each record sheet or leaf is divided on both sides into a series of horizontal writing spaces by lines numbered from 1 to 10, as shown, said lines being divided into vertical columns for separating data concerning checks issued, as, for instance, the date, name of the person to whom the check is made payable, items, amount deposited, and balance. Thus, each of the numbered lines contains the complete data of an issued check.

As the leaves 11 are printed on both sides, the book may be reversed to bring the other sides of the leaves into play, thus extending the utility of the check book and economizing on paper material, as distinguished from books having recording leaves printed only on one side.

One the outside of each of the covers 8 and 9, is printed the indicia

Checks from _____ to _____ 19_____
Nos. from _____ to _____

adapted to be filled out with data concern- 110

ing the checks collectively, said indicia being so printed thereon as to be readable when the cover hangs downward, so that when the latter is swung upward the record leaves to which said data belong will also stand in proper position to be read. Thus, the book need only be reversed to readily refer to data on the other side of the record leaves.

10 The covers 8 and 9 loosely fit the pockets 6 and 7 so that they may be inserted therein, as indicated in Figure 1 of the drawings, the unused or reserve leaves being projected with the cover into the pockets, as clearly indicated in Figure 2.

15 For the purpose of stabilizing or holding the leaf being used, here indicated by the numeral 12, the pocket 7 has diagonally disposed slits 13 cut through the inner wall thereof, one at each corner adjacent the bottom of the pocket. The corners of the record leaf are inserted respectively into these slits, as shown, whereby the leaf is held flat against the outside of the pocket 20 to keep it from turning up to thereby facilitate writing thereon.

25 Referring to Figure 6, 14 and 15 designate the upper and lower covers of a pad of check blanks 16, said check blanks being suitably bound together along their upper edges, and said covers being preferably foldably connected to said pad by means of a flexible strip 17. The checks may be removed one at a time by means of the perforated tearing line 18, extending across the top thereof.

30 The cover 14 is made of blotting paper, the object being the provision of readily accessible blotting means at all times handily positioned for conveniently drying the written matter, both on the check and record leaf.

35 The cover 15 is made of stiff material, which may be termed a backing strip, and is inserted into the pocket 6 over one of the covers of the record book, and such used record leaves as may have been inserted therein, as is clearly shown in Figure 2.

40 In use, the check is made out in the ordinary manner, the blotter 14 having been previously swung upward over the record leaf, as indicated in dotted lines (Figure 2). When the writing of the check is completed, it may be dried by means of the blotter 45 and the data thereof thereafter recorded in the proper place on the face of the exposed record sheet as shown, which in turn may then be dried by the same blotter, by simply swinging the latter upward.

50 A suitable fastener 19, parts of which are carried on the flap 4 and the cover 1, is provided, whereby the flap may be buttoned to said cover to hold the check book closed, as indicated in Figure 5. Thus, I

55 secure a check book, which may be con-

veniently carried in the pocket, is in complete readiness on opening of the covers for writing a check and recording the data thereof, together with handily positioned drying facilities for the writing of each. ⁷⁰

Further, the record book may be easily renewed in that it may be readily withdrawn from the pockets, or a new leaf exposed and held positioned by simply withdrawing it from the pocket and inserting ⁷⁵ it into the slits 13, while the filled out record sheet, is readily slipped into the pocket 6 under the cover of the check pad, to be protected and concealed thereby.

The covers 1 and 2, including the check ⁸⁰ blanks, may be termed a book, within which is removably held a second book constituted by the covers 8 and 9 enclosing the record leaves, the lines of fold 3 and 10, respectively, of said books being approximately ⁸⁵ in register, and the record leaves 11 being held in writing position by means of the slits 13.

I claim:

1. In a check book of the class described, ⁹⁰ the combination with a book having an open pocket on the inside of each of its covers, said pockets opening toward the line of fold between said covers, and another book within said first named book, having its covers projected respectively into said pockets to be thereby removably held foldably positioned therein, a plurality of leaves in the form of checks, bound together along one edge thereof and including a back strip ⁹⁵ extending over the back thereof, superposed on one of said pockets and having its back strip extended into the interior of said pocket, record leaves forming part of said second named book projectable collectively or singly into either of said pockets or extendible freely between the latter, slits in the cover opposite said pad of leaves, to receive the outer corners of the freely extending record leaves to hold the latter in ¹⁰⁰ writing position, and a series of titles printed across the free outer edge of each of said record leaves relating to data commonly forming subject matter of record in the issuance of checks, and ruled lines on said record sheets for dividing said titles into vertical columns. ¹⁰⁵

2. In a check book of the class described, in combination with a book having a pocket on the inside of each of its covers, said pockets opening inwardly, said book including a pad of detachably connected check forms removably secured within its covers, another book having its covers projected respectively into said pockets to be closable collectively with said first named book, record leaves secured in said second named book projectable at will into either of said pockets collectively or singly, or extendible freely between said pockets, and slits in one of ¹¹⁰ ¹¹⁵ ¹²⁰ ¹²⁵

said covers to receive the outer free corners, respectively, of said freely extending record leaves, for the purpose set forth.

3. In a check book of the class described, 5
 5 in combination with a pair of covers having a line of fold between them, a second pair of covers having a line of fold between them superposed upon said first named covers to bring the said lines of fold in 10
 10 register, pockets formed by a wall on said first named covers to loosely receive said second named covers, slits in the wall of one of said pockets, one for each of the outer corners thereof, and record leaves in connection with second named covers adapted 15
 15 to engage with their corners singly or collectively in said slits to be held in writing position thereby, and further adapted to be inserted singly or collectively into either 20
 20 of said pockets.

4. A check book comprising, in combination, an outer book including a pair of foldable covers, an inner book including a pair of foldable covers, within said outer book 25
 25 and foldable collectively with the latter, pockets carried by said outer book to removably receive respectively the covers of said inner book to hold the latter positioned therein, slits in the cover of said outer book, 30
 30 and leaves secured in said inner book adapted to engage in said slits to hold them in flat writing position, a row of titles relating to recordable subject matter concerning checks printed on said leaves, said leaves 35
 35 being ruled into columns to aline with said titles, and substantially similar titles similarly ruled into columns, on the other side of each of said leaves disposed thereon to be rendered readable responsive to a reversal 40
 40 of the book.

5. In a check book of the class described, in combination with the elements set forth in claim 4, of indicia printed on the outside of each of the covers of said inner book, 45
 45 and providing spaces to be filled in for the

recording of the time within which all of the checks were issued and the scope covered by the numbers thereof.

6. In a check book of the class described, in combination, a pair of elongated joined covers, a line of fold longitudinally midway between said covers, a pocket formed by a wall secured to the inside of each of said covers, the openings of said pockets facing said line of fold and being spaced therefrom and parallel therewith, a book of elongated record leaves, including a pair of joined foldable covers, having a line of fold midway between them, said covers removably extending respectively into said pockets to bring their line of fold into register with said first named line of fold, to thereby render both pairs of covers collectively foldable to close them, and said record leaves being projectable, at will, into either 60
 60 of said pockets or therebetween, a series of titles relating to data commonly recorded in the issuance of checks, printed in a line along the outer long edge of each of said record leaves, said record leaves being ruled into 65
 65 columns that aline with said titles, a pad of detachable leaves in the form of checks, including a backing strip extending inwardly from the top edge thereof, said pad superposed on one of said pockets and having its backing strip inserted into the latter to thereby hold it removably positioned thereon, and oppositely disposed slits cut in the wall of the other of said pockets, one at 70
 70 each of the outer corners thereof to receive 75
 75 respectively the outer corners of record leaves not projected into said pockets, said slits inclining inwardly relative to the opening of the slotted pocket.

In testimony whereof I affix my signature in presence of two witnesses.

JOHN O. ELLIOTT.
